UNITED STATES PATENT OFFICE.

JESSE W. RENO, OF NEW YORK, N. Y.

INCLINED ELEVATOR.

963,176.

Specification of Letters Patent.

Patented July 5, 1910.

Application filed June 26, 1909. Serial No. 504,466.

To all whom it may concern:

Be it known that I, JESSE W. RENO, a citizen of the United States of America, and resident of the city, county, and State of 5 New York, have invented certain new and useful Improvements in Inclined Elevators, of which the following is a specification.

My invention relates to inclined elevators.

The object of my invention is to provide 10 an elevator of this class which shall be simple and effective in its construction and operation and in which the individual steps are of a size sufficient to accommodate a passenger's feet and are arranged to travel 15 along a stationary incline and to coöperate at the upper and lower ends of the incline with comb landings whereby the passengers may be conveniently and safely received on and discharged from said steps.

20 Another object of my invention is to provide a simple and efficient means for operating said elevator.

My invention consists in providing a stationary inclined support, a series of steps 25 hinged together in the form of an endless belt, in arranging the tread surfaces of the steps so that when they are in operative position upon the inclined support the surfaces are themselves inclined in the same direction and preferably at about half the 30 angle of the inclination of said support, in providing grooves in the steps arranged in alinement with each other longitudinally of the direction of said tread belt, in providing comb landings at the upper and lower 35 extremities of the incline, in securing sections of rack to the under side of the steps of which the tread belt is composed, in providing a driving pinion adapted to engage 40 said racks to operate said tread belt, and in other novel features and combinations to be hereinafter more fully pointed out and described.

In the drawings accompanying and forming 45 a part of this application, Figure 1 is a side view partially in section of the upper end of an elevator constructed in accordance with my invention, Fig. 2 is a plan of the same, and Fig. 3 is a side view of the 50 lower end.

The reference characters are used in the same sense throughout the drawings and specification.

55 Numeral 1 represents the inclined supporting structure upon which the elevator operates; 2 represents the tread belt. The

tread belt is composed of a series of uniform steps 3 which are hinged together in the form of an endless belt. Each alternate step is provided with a section of rack 4, 60 centrally secured to its under side, and the steps alternating with these are provided with a pair of racks 5. The ends of the double racks 5 overlap the ends of the single racks 4 and these ends are provided with a 65 pin connection 6 by means of which the steps are pivotally connected to each other. A series of grooves 7 is formed in the tread surface of the steps in alinement with each other and parallel to the longitudinal direction of the belt and these grooves register with the prongs 8 of the comb landing. Track rails 9 are secured to the supporting structure and the steps are provided with rollers 10 which are adapted to travel upon 70 said track rails. The tread surfaces of the steps 3 are arranged at an angle to the track so that when the steps are in operative position on the incline the tread surfaces are inclined to the horizontal in the same direction as the said incline and preferably at about half the angle of the said incline. The purpose of this arrangement is to permit the use of integral steps upon a 75 relatively steep incline without increasing the risers an amount, or to an extent, which would be disadvantageous when used in connection with comb landings. By careful experiments I have ascertained that the tread surface of the steps may be inclined as 80 described without interfering with the safety or convenience of passengers and by keeping the risers down to the limits made possible by this construction, the operation at the 85 landings is materially benefited. This is particularly true at the lower landing where 90 passengers are apt frequently, in entering upon the tread belt, to so place their feet that they will rest partly upon one step and partly upon another. Beneath the tread belt and preferably near the upper end of the incline, I provide a pinion 11, mounted on the shaft 12 and adapted to be driven in any convenient manner. This pinion engages the racks secured to the under side of 95 the steps and may be operated to drive the tread belt in either direction.

Having thus described my invention what I claim is:

1. In an inclined elevator the combination 110 with an inclined support, of a tread belt adapted to travel upon said support, said

tread belt being composed of a series of uniform steps having working or tread surfaces flat and inclined from the horizontal in the same direction as said support.

- 5 2. In an inclined elevator the combination with an inclined support, of a tread belt adapted to travel upon said support, said tread belt being composed of a series of uniform steps having working or tread surfaces flat and inclined from the horizontal in the same direction but at an angle less than that of the inclination of said support.
- 10 3. In an inclined elevator the combination with an inclined support, of a tread belt composed of transverse steps having inclined tops linked together, racks secured to said steps and a driving gear adapted to engage said racks.
- 15 4. In an inclined elevator the combination with an inclined support, of a tread belt composed of steps linked together adapted to travel upon said support, a centrally disposed rack, and a pair of racks disposed on either side of the center, secured, respectively, to the under side of alternating steps.
- 20 5. In an inclined elevator the combination

with an inclined support, of a tread belt composed of steps linked together adapted to travel upon said support, a centrally disposed rack, and a pair of racks disposed on either side of the center secured respectively to the under side of alternating steps and a hinge connection between the adjacent ends of the racks on contiguous steps.

30 6. In an inclined elevator the combination with an inclined support, of a tread belt adapted to travel upon said support, said belt being composed of a series of uniform steps having their working or tread surfaces inclined from the horizontal in the same direction as said inclined support and having longitudinal grooves formed therein, and a comb landing adapted to register with said grooves.

35 In testimony whereof, I have signed my name to this specification in the presence of two subscribing witnesses.

JESSE W. RENO.
